(57) **CLAIM**

The ornamental design for a control armrest for lift truck, as shown and described.

DESCRIPTION

FIG. 1 is a left side perspective view of a first embodiment of a control armrest for lift truck;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a right side perspective view thereof.

FIG. 9 is a left side perspective view of a second embodiment of a control armrest for lift truck;

FIG. 10 is a top view thereof;

FIG. 11 is a bottom view thereof;

FIG. 12 is a left side view thereof;

FIG. 13 is a right side view thereof;

FIG. 14 is a front view thereof;

FIG. 15 is a rear view thereof; and,

FIG. 16 is a right side perspective view thereof.

Any broken lines in the figures illustrate portions of the control armrest that form no part of the claimed design.
